US00D663413S

(12) **United States Design Patent**
Amarasinghe

(10) **Patent No.:** **US D663,413 S**
(45) **Date of Patent:** **** Jul. 10, 2012**

(54) **HEADGEAR**(75) Inventor: **Amal S. Amarasinghe**, West Pennant Hills (AU)(73) Assignee: **ResMed Limited**, Bella Vista (AU)(**) Term: **14 Years**(21) Appl. No.: **29/409,066**(22) Filed: **Dec. 20, 2011**

D335,367 S	5/1993	Mieskoski
5,284,469 A	2/1994	Jasen et al.
D351,021 S *	9/1994	Martin .....
5,488,948 A	2/1996	Dubruille et al.
5,490,504 A	2/1996	Vrona et al.
D368,372 S *	4/1996	Dennison .....
5,517,986 A	5/1996	Starr et al.
5,529,062 A	6/1996	Byrd et al.
